U-BOLT CONNECTOR

Herbert E. Hoadley, Joplin, Mo., assignor to A. B. Chance Company, Centralia, Mo., a corporation of Missouri

Application February 4, 1948, Serial No. 6,119

1 Claim. (Cl. 173—273)

1

The present invention relates to U-bolt connectors, and is particularly concerned with the provision of an improved U-bolt connector which is adapted to be manipulated by means of an elongated insulated pole, so that it may be utilized for connecting or clamping two electrical conductors together even though they may be energized from a source of high voltage.

One of the objects of the invention is the provision of an improved U-bolt connector of the class described, which has all of its component parts so mounted that the U-bolt connector can be applied easily, more quickly and more safely, with less liability of the dropping of parts while handling so that it may be utilized with safety in connecting wires which are energized with high voltage.

Another object of the invention is the provision of an improved U-bolt and tool assembly, by means of which such a U-bolt may be handled and applied to high tension wires by utilizing an elongated insulated pole such as, for example, a universal pole of the type having a flanged fitting at its end for receiving various kinds of tools.

Another object of the invention is the provision of an improved clamping connector of the class described, which is simple in construction, adapted to be manufactured at a low cost, durable and which may be removed from the line by means of high tension tools with a minimum amount of difficulty.

Another object of the invention is the provision of an improved clamping connector of the class described, which provides a minimum amount of electrical resistance at the point of connection and which is adapted to clamp the conductors uniformly substantially without damage to either conductor, but with a relatively firm and permanent electrical connection of low resistance.

Other objects of the invention will be apparent from the following description and the accompanying drawings, in which similar characters of reference indicate similar parts throughout the several views.

Referring to the drawings of which there are two sheets,

Fig. 1 is a side elevational view in partial section, showing a U-bolt connector embodying the invention assembled with an adapter and tool which may be attached to a universal operating pole so that the connector may be handled on high tension lines by merely providing a new adapter and a new tool for the universal pole usually carried by linemen;

2

Fig. 2 is a view similar to Figure 1, with the connector in closed clamping position;

Fig. 3 is a fragmentary sectional view taken on the plane of the line 3—3 of Figure 1, looking in the direction of the arrows;

Fig. 4 is a top plan view of the upper clamping member;

Fig. 5 is a view in perspective of the intermediate clamping member or spacer;

Fig. 6 is a view in perspective of the lower clamping member;

Fig. 7 is a side elevational view of a modification;

Fig. 8 is an end elevational view of the modification of Figure 7, taken from the left side of Figure 7;

Figure 9 is a top plan view of the device of Figure 7;

Fig. 10 is a sectional view taken on the plane of the line 10—10 of Figure 7, looking in the direction of the arrows; and

Fig. 11 is a sectional view taken on the plane of the line 11—11 of Figure 7, looking in the direction of the arrows.

25 Referring to Figures 1 to 6, the U-bolt connector which forms the subject of the invention is indicated in its entirety by the numeral 23, and it preferably comprises the following parts: U-bolt 21, upper clamping member 22, intermediate clamping member 23, lower clamping member 24, spring washers 25, 26 and nuts 27, 28.

30 The U-bolt 21 may consist of an elongated cylindrical rod bent to substantially U-form and provided with threaded ends 29, 30. The U-bolt 35 may be made of any suitable metal, such as galvanized iron, or of metal of high electrical conducting properties, such as copper alloys or aluminum.

35 The threaded end portions 29 and 30 are provided with complementary nuts 27 and 28 which engage standard spring washers 25 and 26. The spring washers assure the holding of the nuts in permanent position against loosening by rattling, and the spring washers also serve to take up any looseness or space between the clamping members and the conductors which may be due to wear or change of shape or other causes.

To increase the bearing surface of the spring washer 26 against the lower clamping member, this leg of the U-bolt is preferably provided with a washer 27. The two legs of the U-bolt may be separately indicated by the numerals 31 and 32, and the easy bend or yoke portion by the numeral 33.

45 The upper clamping member 22 is shown in top plan in Figure 4, and in cross-section in Fig-

ure 3. It comprises a cast metal member which is adapted to fit inside the U-shaped bend 33 of the U-bolt 21. For this purpose the top clamping member 22 is formed with a pair of half-cylindrical flanges 34, 35, located on either side of a half-circular groove 36, but the groove 36 extends about the periphery of the top clamping member 22 in a half-circle and is a substantial fit with the inner surface of the U-shaped bolt at the easy bend 33.

The length of the top clamping member 22 is preferably such that it protrudes from both sides of the space between the U-bolt, and on its lower surface it has a substantially partially cylindrical groove 37 which has tapered inlet portions 38 at each end. The size of the groove 37 is such that there is substantially the same curvature for the groove 37 as the curvature of the conductors 39 and 40 that are to be engaged by the connector.

In order to guard against the loss of the top clamping member 22, this top clamping member has its peripheral flanges 34 and 35 provided with radially projecting fingers 41, 42, 43, 44. The characteristics of the metal and the thickness of the fingers 41—44 are such that these fingers may be bent over the portion 33 of the U-bolt 21, and thus the groove 36 for the U-bolt embraces more than half a circumference of the U-bolt, and the top clamping member 22 is secured to the U-bolt.

The intermediate clamping member or spacer 23 may consist of a cast metal member having a substantially rectangular central portion 45, the upper and lower flat surfaces 46 and 47 of which are provided with transversely extending partially cylindrical grooves 48 and 49. Groove 48 is adapted to engage the bottom of the upper conductor, and groove 49 is adapted to engage the bottom lower conductor 40. Figure 2.

The rectangular body 45 of clamping member 23 is provided with a laterally extending pivot flange 50 having a centrally located cylindrical through bore 51, by means of which this clamping member is pivotally mounted on the right leg 31 of the U-bolt. The rectangular body 45 is also preferably provided on the side opposite to the pivot flange 50 with a stop flange 52, which may comprise an outwardly tapered flange having a plane stop surface or shoulder 53 for engaging the front side of leg 32 of the U-bolt 21.

When the stop surface 53 engages leg 32, the groove 48 is in substantial alignment with the groove 37 in the upper clamping member 22, and both grooves extend at right angles to the plane which is defined by the axis of the U-bolt.

Referring to Figure 6, this is a view in perspective of the lower clamping member. It may comprise a cast metal member having a relatively thick body 54, with a plane upper surface 55 and a plane lower surface 56. The upper surface 55 is provided with a transverse partially cylindrical groove 57, the ends of which are enlarged, as shown at 58. This groove is adapted to engage the lower side of the lower conductor 40. Figure 2.

The body 54 has a triangular extension at the right of groove 57 (Figure 6) which is provided with a through bore 59, whereby this clamping member may be pivotally mounted on the right-hand leg 31 of the U-bolt. At its opposite side, that is, toward the left of the groove 57, the body 54 is formed with a laterally open groove 60 of partially cylindrical shape open at the rear side 61 but adapted to engage and have a substantial

fit against the leg 32 of the U-bolt. When the groove 60 receives the leg 32 of the U-bolt then the conductor groove 57 is in alignment with the conductor grooves 37, 48 and 49 of the other clamping members.

The hooked shaped formation 62 which forms the groove 60 is preferably tapered at its upper surface, as indicated at 63 (Figure 1) so that the tapered surface 63 may serve as a camming surface, readily engaging under the conductor 40 and camming it upward until the conductor 40 rides into the groove 57, with the parts in the position of Figure 2.

Referring to Figures 7 to 8, these are views showing a modification which differs from that described with respect to Figures 1 to 6 as follows: In this case the U-bolt 21 may be identical in form and shape, but the upper clamping member 64 has its peripheral flanges 65, 66 each provided with a single finger 67 or 68 for clamping this upper clamping member on the U-bolt 21.

The threaded portions 30, nuts 27, 28, spring washers 25, 26, may be identical with those of Figure 1. The lower clamping member 69 is similar in shape to that previously described, and has a central groove 70 of similar form, but both of the end flanges are tapered in thickness at 71 and 72 so that groove 70 is located in a central relatively thick portion 73.

The tapered flange 71 has a through bore 74 whereby clamping member 69 is pivotally mounted upon the U-bolt 21. The tapered flange 72 has a forwardly open partially cylindrical groove 75 (Figure 11) which engages about the other leg of the U-bolt 21. The central groove 70 (Figure 11) is bordered by parallel ribs 76, 77. The lower surface 78 of the lower clamping member is preferably plane to give a maximum bearing surface against the spring washers 25, 26.

The intermediate clamping member 79, in this case, may consist of an elongated metal member of sufficient width to pass between the legs 80, 81 of the U-bolt. This elongated intermediate clamping member is provided with a lower groove 82 and an upper groove 83 of sufficient size to receive the conductors 84, 85.

This intermediate clamping member is not pivotally mounted on either leg of the U-bolt, but has a pair of laterally projecting stop members 86, 87 which engage the legs of the U-bolt when this clamping member is inserted between the conductors 84, 85. Such insertion may be made by means of a suitable tool in the installation of the U-bolt connector.

Referring now to Figure 1, the U-bolt connector is shown here in connection with a tool assembly 88, which may be utilized with the standard universal operating pole for manipulating high tension line tools. Such a pole (not shown) consists of an elongated pole of wood serving as an insulator, and provided at its upper end with a tubular cast metal fitting having an axially extending disk with a threaded bore and a thumb bolt.

The disk has radial serrations or ridges and grooves for engaging the ridges and grooves 89, 90 of a complementary disk formation 91, which has a longitudinal slot 92 for receiving the thumb bolt by means of which the universal pole and disk formation 91 are clamped together. They may be clamped in various angular positions.

The tool assembly 88 preferably includes a universal pole tool 93 and an adapter 94. The

tool 93 includes the supporting disk 91, just described, and a radially extending cylindrical body 95 provided with an axial bore 96 for receiving the adapter.

The extension 95 is preferably provided with a set screw 97 threaded into a threaded bore in the wall of the extension 95, and protrudes into the bore 96 to engage the shank 98 of the adapter 94. Thus the adapter may be secured to the universal tool 93 against rotation or against removal.

The adapter 94 is provided in order that the same tool 93 may be used for U-bolts having bolts of different sizes. Each adapter may consist of an elongated cylindrical member having a socket 99 for the set screw 97, the cylindrical member fitting in the bore 96.

At its open or free end the adapter 94 is provided with an axial threaded bore 100, and the bore 100 is complementary to the threaded ends 29 or 30 of the U-bolt. If a bigger U-bolt is to be employed an adapter will be used having a larger bore 100 to fit the U-bolt. The adapter 94 is threaded on the end 29 of the U-bolt 21 until it engages the nut 27.

It should be noted that the adapter and tool are attached to the leg 31 of the U-bolt, which is the leg upon which the intermediate clamping member 23 and the lower clamping member 24 rotate, leaving the U-bolt open, as shown in Figure 1, for application to a pair of conductors.

One method of utilization of the tool assembly with the U-bolt of Figure 1 is as follows: A tap conductor 39 may be placed below the groove 37 in the U-bolt, and the clamping member 23 may be swung around to the position of Figure 2 below the conductor 39 for temporarily supporting the conductor. The conductor should have a laterally bent end portion for preventing it from sliding out of the U-bolt endwise. At this time the clamping member 23 will slide down on leg 31 until it is engaged with clamping member 24.

Assuming that the tool assembly 93 has been secured to the U-bolt and has been mounted upon a universal pole, the operator may then use the pole to lift the U-bolt and the tap conductor, the latter being supported above the clamping member 23. The U-bolt is placed over the line conductor and drawn downward by means of the universal pole. The line conductor 40 will then engage the lower groove 49 in the intermediate clamping member 23, and the downward force on the U-bolt assembly will cause clamping member 23 to slide upward into the position of Figure 2, being held by the line conductor 40. Then the operator may use some other appropriate line operating pole, such as a clamp stick or disconnect stick, to rotate the lower clamping member 24 from the position of Figure 1 to that of Figure 2.

Thereafter, with the tool assembly 93 still holding the connector, a second universal pole may be provided with a socket wrench and the wrench may be applied to the nut 28 which may be tightened, driving the clamps 23 and 24 upward and clamping the conductors.

After one of the nuts 28 has been tightened the supporting tool assembly 93 may be removed from the other U-bolt leg 31 by turning the universal pole counterclockwise. This will remove the threaded socket 100 from the threaded portion 29 of the leg 31. By this time the U-bolt may be supported with sufficient fixity on the conductor 40 so that socket wrenches may be

applied to the nuts 27 and 28 to tighten both of these nuts until all of the space is taken up which would be occupied by the spring washers 25, 26 in their expanded condition.

5 The U-bolt is then tightly clamped on the conductors and the nuts are held by the spring washers. The spring washers are ready to take up any slack that might occur between the clamping members and conductors, and the connector cannot be loosened by any rattling or other movements which occur in service. At the same time the connector can again be removed at will by applying a socket wrench to the U-bolt connector nuts.

15 The same procedure may be used in applying the U-bolt connector of Figures 7 to 11 with the same tool assembly 93. Bearing in mind, however, that in this case the intermediate clamping member is not pivotally mounted on either bolt. The tap wire 85, for example, Figure 10, should have its lower end 101 bent laterally so that the tap wire tends to pull the clamping member 79 into the U-bolt. Then the U-bolt and tap wire 85 may be lifted exactly as described, and the clamping member 69 pivoted to the position of Figure 7 after the U-bolt has been hooked over the line conductor 84.

20 It will thus be observed that I have invented in improved U-bolt connector, the parts of which are so coordinated with respect to each other that there is very little possibility of any of these parts becoming lost. The U-bolt connector is adapted to provide a very tight and relatively permanent electrical connection between electrical conductors, which it clamps without damage to the conductors.

25 By means of the improved tool assembly this U-bolt connector can be manipulated with a universal insulating pole so that it can be applied without danger to an energized high tension line conductor. The clamping members which engage the conductors may be made of any suitable material, such as copper or aluminum alloys, depending upon the material of which the line conductor is made.

30 While I have illustrated a preferred embodiment of my invention, many modifications may be made without departing from the spirit of the invention, and I do not wish to be limited to the precise details of construction set forth, but desire to avail myself of all changes within the scope of the appended claim.

Having thus described my invention, what I claim as new and desire to secure by Letters 35 Patent of the United States, is:

30 In a U-bolt connector, the combination of a substantially cylindrical U-bolt member having both of its ends threaded, and said U-bolt member being bent to provide a partially circular 60 yoke portion which supports a pair of parallel threaded legs, a threaded member on each of said legs, a lower clamping member comprising a cast metal member formed with an aperture for receiving the first leg whereby it is pivotally 65 mounted on said first leg, said lower clamping member having a transverse open slot for engaging the other leg and having a relatively wide central portion with a substantially semi-cylindrical groove for engaging an electrical 70 conductor, said lower clamping member having an upper surface tapering upwardly from said slot, an intermediate cast metal clamping member formed with a flat body of sufficient thickness to be provided on its upper and lower sides 75 with semi-cylindrical grooves for engaging elec-

trical conductors, said intermediate clamping member having means for engaging both of the legs of the U-bolt for maintaining it in alignment with the other two clamping members, and a third clamping member comprising a cast metal member formed with a central elongated body adapted to be received between the legs of the U-bolt and formed with a lower elongated groove opposing the upper groove in the intermediate clamping member, said third clamping member having its top and sides formed with a groove which is semi-circular in cross section for a sliding fit on the yoke of the bolt, the said latter groove extending peripherally about the upper part of the third clamping member in an arcuate direction complementary to the partially circular portion of the U-bolt, this clamping member being rotatable on the U-bolt about the center of curvature of the bent portion of the U-bolt, to adjust itself automatically to the best gripping position on a conductor located in its groove, the said third clamping member having outwardly extending fingers which embrace an outer part of the bent bolt portion to retain this clamping member on the U-bolt, all of the grooves in the said clamping

members extending substantially at right angles to the plane in which the two legs of the U-bolt have their axes located.

HERBERT E. HOADLEY.
